COMBINED SHELF AND PAPER ROLL HOLDER

Sylvan S. Davis, Bellaire, Tex., assignor to Davis-Freeman Company, Inc., Houston, Tex., a corporation of Texas

Filed Apr. 19, 1963, Ser. No. 74,532

Term of patent 14 years

(Cl. D4—3)

FIGURE 1 is an isometric view of the top and one side of a combined shelf and paper holder, showing my new design; and

FIGURE 2 is an isometric view of the bottom and opposite side thereof.

The rear is flat and plain, with the exception of the two longitudinal ribs in FIGURES 1 and 2.

I claim:

The ornamental design for a combined shelf and paper roll holder, as shown and described.
